UNITED STATES PATENT OFFICE.

WILLIAM J. STAMM, OF LEHIGHTON, RICHARD L. EUSTICE, OF NESQUEHONING, AND
GEORGE GARDINER, OF LANSFORD, PENNSYLVANIA.

SAFETY DEVICE FOR ELECTRIC SWITCHES.

1,197,562.

Specification of Letters Patent.

Patented Sept. 5, 1916.

Application filed February 12, 1916. Serial No. 77,889.

To all whom it may concern:
Be it known that we, (1) WILLIAM J. STAMM, (2) RICHARD L. EUSTICE, and (3) GEORGE GARDINER, citizens of the United States, residing, respectively, at (1) Lehighton, (2) Nesquehoning, and (3) Lansford, in the county of Carbon and State of Pennsylvania, have invented new and useful Improvements in Safety Devices for Electric Switches, of which the following is a specification.

This invention relates to a safety device or covering for electric switches such as a knife switch, and the object of the invention is to produce a device of this character which shall be fire-proof, moisture proof and which shall be so arranged to surround the switch as to prevent any part of the operator or other person contacting with the end of the energized wires or the parts of the switch, and so render the same entirely safe.

A further object of the invention is to construct a device of this class whereby the handle of the switch blade may be effectively locked to prevent unauthorized persons tampering with the switch.

With the above and other objects in view, the improvement resides in the construction, combination and arrangement of parts set forth in the following specification and falling within the scope of the appended claims.

In the drawings: Figure 1 is a perspective view of a knife switch protected in accordance with the present invention, the switch being locked in one position, Fig. 2 is a central vertical longitudinal sectional view through the same, the switch being thrown to its operable position, Fig. 3 is a bottom plan view of the same, Fig. 4 is a transverse sectional view approximately on the line 4—4 of Fig. 2, Fig. 5 is a detail transverse sectional view approximately on the line 5—5 of Fig. 1, and Fig. 6 is a perspective view of the spacer strip.

All of the parts comprising our improvement, excepting the attaching elements, such as the screws, etc., are constructed from some suitable insulating material, and while in the accompanying drawings we have illustrated our improvement in connection with a single blade switch, it is to be understood that the same may be successfully employed in connection with all classes of knife or other switches on feed lines,

light lines or upon switch-boards in substations or power houses.

In the drawings, the numeral 1 designates a substantially rectangular panel which is provided at its corners with depending legs 2, the legs having offset feet provided with apertures whereby the device may be secured to a suitable support 3. The legs 2 are adapted to prevent the sliding band, hereinafter referred to, from contacting with a support, as for instance, when the device is to be secured upon a wall or the like, and these legs may be dispensed with when the improvement is employed upon a switch-board.

The switch is indicated by the numeral 4 and is centrally secured upon the panel 1, and the numeral 5 designates a knife member or blade of the switch. The switch is of the ordinary construction.

Secured to the panel on the opposite side of the longitudinally arranged switch 4 are side members 6. These members are preferably connected to the panel 1 by threaded elements entering from the bottom or rear face of the panel so that either of said members may be removed and access may be obtained to the switch, and the wires 7 leading to the switch are insulated and passed through suitable openings in one of the sides 6. Each of the sides 6 upon its inner face is provided with an outer and an inner arch-shaped strip 8 and 9 respectively, the said strips being spaced from each other to provide oppositely disposed parallel grooves to receive the opposite edges of a split ring or protective band 10. The band passes through suitable openings 11 in the panel 1, the said openings registering with the space between the guide strips 8 and 9, and by such an arrangement it will be noted that the band 10 entirely surrounds the switch but may be freely revolved in the grooves provided between the strips 8 and 9 of the side members 6 as well as through the openings 11 in the panel 1. The ends of the split band 10 are connected by a plate 12 which is of a less width than the band 10, and the securing elements 13 which pass through the band and through the ends of the curved plate 12 are received in transverse depressions 14 formed upon the inner face or adjacent the opposite ends of a guide or spacer strip 15. The strip 15 is adapted to contact with the outer arch-shaped strips 9 of the

side members 6 and so prevents any binding between the band 10 and the strips 8 and 9 of each of the sides. The knife blade is of a length to contact with the inner face of the band 10 and the said end is preferably enlarged and provided with a threaded opening. The numeral 17 designates an insulated handle which is arranged upon the outer face of the band 10 and which contacts with the spacer strip 15. This handle is provided with a threaded shank 16 that passes through a suitable opening in the band 10 and is received in the threaded head of the knife blade. The shank 16 for the major portion of its length is square in cross section, the purpose of which will presently be described. Centrally secured to the inner face of the panel 1 and projecting at a right angle therefrom is a plate 18, the same having its outer end slotted or bifurcated and the inner wall provided by the said slot or bifurcation round to contact with and provide a tension member as well as a guide for the portion of the band 10 extending beyond the inner face of the panel 1, and the side members or fingers 19 formed by the said slot or bifurcation in the member 18 provide the side members of the band. By this arrangement it will be noted that as the handle is operated the band will be revolved with the swinging of the knife blade 5; that the band and sides entirely close the metal parts of the switch and that access to the switch cannot be obtained until one of the sides 6 is removed.

In some instances it has been found necessary or desirable to lock the switch in either its open or closed position and to provide for this we arrange upon the panel 1 at one 40 of the sides of the casing provided by the sides 6 and the band 10, a stand 20, the same having its outer end bifurcated to provide spaced arms 21 and 22 respectively. The arm 21 is of a less length than the arm 22 and has its corners notched to receive the ends of a hasp member 23 which is pivotally secured to the said corners. The arm 22 has its end also reduced to provide an extension 24 that is adapted to be received 45 between the arms of the hasp 23, the said extension having an opening 25 to receive the shackle of an ordinary lock. The 50 squared portion of the shank 16 of the handle 17 is adapted to be received between the arms 21 and 22 before, of course, the hasp is swung over the arms and locked thereon, and the squared portion of the shank will prevent the unlocking of the handle from the knife blade, as will be read- 55 60 ily understood.

Having thus described the invention, what we claim is:

65 1. In a knife switch, a protective casing of insulated material surrounding the same said casing including spaced sides and a con-

tinuous band revoluble around the sides, and a handle of insulated material upon the exterior of the band and connected with the knife blade of the switch.

2. In a knife switch, a protective casing 70 of insulated material surrounding the same, said casing including spaced sides and a continuous band revoluble around the sides, a handle of insulating material for the band, a connection between the handle and the 75 knife blade of the switch, and means for locking the handle to retain the blade of the switch in one position.

3. A protective device for knife switches including in combination with a knife switch, a panel upon which the switch is secured, members extending from the panel to the opposite sides of the switch, and a continuous band passing through openings in the panel and received in grooves in the sides and surrounding the switch, an insulated handle for the band, and a connection between the handle and the knife blade of the switch. 80 85

4. A protective device for knife switches 90
constructed of insulating material including
a panel to which the switch is secured, side
members for the panel upon the opposite
sides of the switch, a split band passing
through openings in the panel and received 95
in grooves in the side members to inclose the
switch between the side members, a plate
connecting the ends of the band, a spacer
member arranged over the plate and contact-
ing with the inner walls of the side mem- 100
bers, a switch having its knife blade pro-
vided with a threaded end which passes
through openings in the meeting ends of the
band, a connecting member for the said ends
and the spacer member, and a handle of in-
sulated material having a threaded socket
receiving the said threaded end of the knife
blade. 105

5. In an insulating protector for knife switches, a panel, a switch secured to the panel, members connected with the panel and arranged to the opposite sides of the switch, a continuous band passing through openings in the panel received in guide grooves in the side members, a connection between this band and the blade of the switch, a handle for the band, and a guide member for the band projecting from the inner face of the panel and having spaced arms engaging with the opposite edges of the band. 110 115 120

6. In an insulating protector for knife switches, a panel, legs arranged upon the corners of the panel and extending in one direction therefrom, a knife switch upon the face of the panel opposite that provided with the legs, side members upon the panel disposed to the opposite sides of the switch, a continuous band passing through openings in the panel and having its edges received

in guide slots in the sides, a connection between the knife blade of the switch and the band, a handle for the band, means upon the panel for locking the handle to retain the knife in one position, and a spacer member secured to the panel and projecting in the direction of the legs contacting with the band.

7. In an insulating protector for knife switches, the combination with a knife switch, of a casing including a member upon which the switch is secured and having sides at the opposite sides of the switch, and a continuous band mounted in guide grooves in the sides and in the base of the casing, a connection between the knife switch and the bands, a removable handle having a square

shank for the band, a standard upon the casing having a slotted end to receive the square portion of the handle, a swinging 20 hasp connected with one of the arms of the stand and adapted to be swung over the other arm and to hold the shank of the handle between the arms of the stand, and means for locking the hasp to one of the 25 arms of the stand.

In testimony whereof we affix our signatures in presence of two witnesses.
